UNITED STATES PATENT OFFICE

2,142,842

FAN

Milton E. Hanson, Collingswood, N. J., assignor
to B. F. Sturtevant Company, Boston, Mass.

Application November 9, 1937, Serial No. 173,648

4 Claims. (Cl. 230—117)

This invention relates to fans and relates more particularly to fans having air inlets on each side of one set of blades whereby two separate air streams may be drawn into the blades and discharged in one stream.

In air conditioning and in pressure ventilating systems, it is desirable to mix recirculated air with the primary air prior to the discharge of the air into the space served, for the purpose of tempering the primary air. Heretofore, in supplying mixed recirculated and primary air, it has been the practice to use a relatively large fan with single inlet, the primary air and the recirculated air being led to the fan inlet through ducts which join adjacent the fan inlet.

A feature of this invention resides in the mixing of recirculated air and primary air in a fan without requiring a duct for supplying the recirculated air.

According to this invention, a fan is provided which may be suspended over the space to be served, and which draws recirculated air directly from the space served, and primary air from a suitable source, and discharges the mixed air without drafts into the underlying space.

Another feature of the invention resides in the provision of means for independently varying the volumes of primary air and of recirculated air drawn in by the fan.

Another object of the invention is to provide a fan which draws in recirculated air directly from the space served and which also draws in primary air for mixture prior to its discharge, with the recirculated air.

Another object of the invention is to provide a decorative yet effective fan which may be mounted in or adjacent the ceiling of an enclosure.

Other objects of the invention will be apparent from the following description taken with the drawings.

The invention will now be described with reference to the drawings, of which:

Fig. 1 is an elevation view in section of a rail-way passenger car equipped with fans embodying this invention, in a pressure ventilating system;

Fig. 2 is a plan view looking downwardly upon a portion of the car of Fig. 1;

Fig. 3 is an enlarged sectional view taken along the lines 3—3 of Fig. 2;

Fig. 4 is a sectional view of one embodiment of

a fan according to this invention, taken along the lines 4—4 of Fig. 5;

Fig. 5 is an elevation view in section of the fan of Fig. 4, and

Fig. 6 is a plan view looking from underneath, 5 of the fan.

Referring first to Figs. 4, 5 and 6, the fan comprises the downwardly pitched, centrifugal blades 10 which are mounted on the shaft 11 of the electric motor 12. The upper casing 13 formed 10 as a frustum of a cone, diverging with respect to the in-coming air flow, provides the air inlet passage to the blades 11 for the primary air which in the embodiment illustrated by Figs. 1 and 3 is outdoor air supplied by the passage 14 15 between the ceiling 15 and roof 16 of the car.

The lower casing 17 formed as the frustum of a cone, converging with respect to air flow, forms the inlet passage into the blades 11 for recirculated air.

The upper casing 13 and the lower casing 17 together and between each other, form a downwardly pitched diverging air outlet passage from the fan. This ensures that the air from the fan is discharged angularly downward into the passenger space. The angularly pitched fan blades enable such a discharge passage to be provided.

Mounted cross-wise the lower portion of the casing 17 and attached thereto, is the plate 18, provided with the plurality of apertures 19. Rotatably mounted at 20 upon the plate 18 is the plate 21, provided with the plurality of apertures 22 which correspond in number, size and shape with the apertures 19 in the plate 18. The plate 18 has the slot 23 through which the bolt 24 attached to the plate 21 extends. The position of the apertures 22 with respect to the apertures 19 is varied by movement of the bolt 24 in the slot 23 by pressure upon the nut 25. The corresponding apertures may be placed exactly in alignment 40 or may be placed completely out of alignment by movement of the bolt 24 in the slot 23. When corresponding apertures are in alignment, the maximum volume of recirculated air is drawn in by the fan and when the corresponding apertures are completely out of alignment, no recirculated air is drawn in by the fan. For intermediate adjustments, volumes of recirculated air below the maximum are drawn in by the fan, the volume depending, of course, upon the degree 50 of over-lap of corresponding apertures. When the desired adjustment has been made, the plate 21 is locked against further movement by screwing up the nut 25 upon the bolt 24 so as to bind the plates 21 and 18 together.

The member 28 above the upper casing 13 is provided with a plurality of apertures 29 similar to the apertures 19 in the plate 18. The plate 31 is attached to the member 28 by the rivets 30 which are loosely fitted in a slot in the plate 31 and in holes in the member 28 so that the plate 31 may be rotated with respect to the member 28 by means of the handle 33 which may be an extension of the plate 31. The plate 31 is provided with the plurality of apertures 32 which are similar to the apertures 22 in the plate 31. By moving the handle 33 which extends through a slot in the bracket 34, corresponding apertures in the plate 31 and the member 28 may be placed in or out of alignment for varying the volume of primary air drawn in by the fan blades, or for shutting off the supply of primary air.

The air drawn in axially by the fan blades 10 is discharged at the outermost edges 26 of the blades 10 through the diverging space, with respect to air flow, between the lower surface of the upper casing 13 and the upper surface of the lower casing 17. The downwardly pitched air discharge passage so provided enables the air to be directed positively into the passenger space, but at such a slight angle, that no drafts are produced.

The lower casing 17 is supported from the upper casing 13 by the members 27 which may be bolted as at 38 to the casing 17 and may be secured in any suitable manner as by welding to the upper casing 13. The members 27 also serve as a decorative shield for the fan as shown by Fig. 6.

The fan is adapted to be placed in a circular opening in the ceiling 15, and supported from the ceiling by the plurality of bolts 36 which extend through the fan bracket 34. The member 28 together with the bracket 34 closes off the space in the circular ceiling opening so that the primary air can enter the fan blades only through the apertures 32.

Figs. 1, 2, and 3 illustrate the application of several of the fans of this invention for providing pressure ventilation for a railway passenger car. Outdoor air enters the inlets 39 in the roof 16 of the car and passes through the filters 37, mounted in longitudinal walls and then into the passage 14 serving as a fresh air supply duct. The plurality of fans are mounted in circular openings in the ceiling 15 serving as the lower wall of the duct or passage 14. The fans may project the primary air without mixture with recirculated air into the car; may project mixed air into the car, or may recirculate the car air, as desired. Mixture of the recirculated air with the primary air serves two useful purposes: the primary air

when too cool is tempered by mixture with the warmer recirculated air, and the drawing in of the recirculated air by the fans causes greater air movement and better air distribution of the air in the car.

While one embodiment of the invention has been described for the purpose of illustration, it should be understood that the invention is not to be limited to the exact arrangement described, as many departures and modifications will suggest themselves to those skilled in the art, after having had access to this disclosure.

What is claimed is:

1. A centrifugal fan for mounting in a perforated ceiling, comprising a motor having a vertical shaft, a fan wheel mounted on the lower end of said shaft, an annular supporting member for attaching said fan to said ceiling, means for supporting said motor from said member, air guiding means around said wheel, and means for supporting said air guiding means from said member.

2. A centrifugal fan for mounting in a perforated ceiling, comprising a motor having a vertical shaft, a fan wheel mounted on the lower end of said shaft, air guiding means extending circumferentially around said wheel, supporting means extending circumferentially around said air guiding means for attaching said fan to said ceiling, and means for supporting said motor and said air guiding means from said supporting means.

3. A centrifugal fan for mounting in a perforated ceiling, comprising a motor having a vertical shaft, a fan wheel mounted on the lower end of said shaft, air guiding means extending circumferentially around said wheel, supporting means extending circumferentially around said air guiding means and between same and said motor for attaching said fan to said ceiling, and means for supporting said motor and said air guiding means from said supporting means.

4. A centrifugal fan for mounting in a perforated ceiling, comprising a motor having a vertical shaft, a fan wheel mounted on the lower end of said shaft, air guiding means extending circumferentially around said wheel, means having a horizontal portion for attachment to said ceiling and having upwardly extending and downwardly extending portions extending circumferentially around said air guiding means and between same and said motor for attaching said fan to said ceiling, and means for supporting said motor from said upwardly extending portions and for supporting said air guiding means from said downwardly extending portions.

MILTON E. HANSON.
